CLOTHES-DRYING APPARATUS

Siegfried E. Manecke, Mansfield, Ohio, assignor
to Westinghouse Electric Corporation, East
Pittsburgh, Pa., a corporation of Pennsylvania

Application May 12, 1951, Serial No. 226,037

3 Claims. (Cl. 34—45)

1

This invention relates to clothes drying apparatus and has for an object to provide improved apparatus of this kind.

A further object of the invention is to facilitate adjustment of the apparatus for the damp drying or complete drying of the clothes being treated.

In practicing the invention, a motor-driven timer is provided for the control of the air circulating motor and the air heating means of the dryer. For damp drying of the load, the timer is adjusted from an inactive position to selective active stations for varying the duration of the periods of operation of the air circulating motor and the air heating means. Accordingly, the amount of moisture remaining in the clothes may be varied, as desired, to best condition the clothes for immediate ironing. When storing of the clothes as they come from the dryer is desired, substantially all moisture should be removed. For this operation, the timer may be adjusted to an additional station wherein the air heating means and air circulating means are operated while the motor of the timer is deenergized. Thermostatic means is provided for starting operation of the timer motor only when the temperature of the air within the drying chamber is elevated to a predetermined value obtaining when the load is completely dried. Operation of the timing motor then terminates operation of the air heating means. Preferably, operation of the air circulating motor continues for a period to cool the clothes. Finally, the air circulating motor and the timer motor are deenergized to terminate the drying cycle.

The foregoing and other objects are effected by my invention as will be apparent from the following description and claims taken in connection with the accompanying drawings, forming a part of this application, in which:

Fig. 1 is a vertical sectional view of a clothes dryer controlled in accordance with this invention, portions of the dryer being shown diagrammatically for the sake of clearness and brevity;

Fig. 2 is a diagrammatic view of the control apparatus for the dryer shown in Fig. 1; and

Fig. 3 is a diagram illustrating the sequence of operation of the control switches shown in Fig. 2.

Reference will now be had to Fig. 1 of the drawing, wherein I have elected to show my invention applied to a clothes dryer of the so-called domestic type and generally of conventional construction. This type of dryer usually includes a casing structure 10 having a generally cylindri-

cal baffle 11 arranged therein for enclosing a drying chamber 12. The drying chamber 12 is provided with an air inlet duct 13 for conveying heated air to the chamber 12 and an air discharge duct 14 for conveying vitiated moist air therefrom. A generally cylindrical basket 15 is arranged within the drying chamber 12 and mounted for rotation about a horizontal axis. It will be understood that the cylindrical side wall 10 of the basket is perforate substantially throughout its extent for the passage of air from the air inlet duct 13 through the basket 15 to the discharge duct 14. The basket 15 is preferably provided with a plurality of radially inwardly extending vanes 16 for tumbling the fabrics during the drying operation. The casing 10 and basket 15 have openings (not shown) formed therein for providing access to the interior of the basket 15.

20 The basket is suitably journaled in the casing 10 for rotation about a horizontal axis and is driven by a sheave 17 belted, as shown at 18, to an electric motor 19 supported by the bottom of the casing 10. The motor 19 also functions to drive a blower runner 21 which is arranged within a blower housing 22. The latter is provided with an air inlet opening 23 which communicates with the space within the casing 10, which space receives air from the surrounding atmosphere through openings 24 formed in the casing side wall. The blower housing 22 discharges into a generally horizontal duct 25 within which an electric heater 26 of suitable construction is disposed for heating the air discharged by the runner 21. The heated air passes through the duct 13 to the drying chamber 12 and to the interior of the basket 15 for contacting the tumbling fabrics.

In accordance with my invention, operation of the air circulating motor 19 and the air heater 26 is under control of a timing mechanism, indicated generally at 27, and a thermostatically-operated switch 28. The latter is open when relatively cool and is actuated to its closed position in response to a predetermined high temperature of the air within the drying chamber 12. When damp drying of the clothes is desired for the immediate ironing thereof, the control of the motor 19 and heater 26 is effected solely by the timer 27. When complete or "bone" drying of the clothes is to be effected, the motor 19 and heater 26 are controlled conjointly by the timing mechanism 27 and the thermostatically-operated switch 28.

Reference will now be had to Fig. 2 of the

drawing which diagrammatically shows the construction of the timing mechanism 27 and the wiring of the dryer. The source of power for the apparatus is represented by line conductors L₁, L₂ and N which usually is an Edison three wire circuit having a potential of 230 v. between the conductors L₁ and L₂ and a potential of 115 v. between the conductors L₁ and L₂ and the neutral conductor N. The timer 27 includes a plurality of switches 31, 32 and 33 which are opened and closed by respective cams 34, 35 and 36. The latter are carried by a rotatable shaft 37 which is driven by a timing motor 38 of the type usually employed for the operation of clocks. A speed reducing mechanism, generally indicated at 39, is interposed between the motor 38 and the shaft 37. The shaft 37 may also be manually rotated by a knob 41 and, to permit this operation, a slip clutch, indicated at 42, is interposed between the shaft 37 and the speed reducing mechanism 39.

As clearly shown in Fig. 2, the stationary contact of the switch 32 is directly connected to the line conductor L₂ while the movable contact thereof is directly connected to one terminal of the heater 26. The opposite terminal of the heater 26 is connected by a conductor 43 to the stationary contact of switch 33. The movable contact of switch 33 is connected by means of a conductor 44 with one terminal of the timing motor 38, the opposite terminal of which is directly connected to the neutral conductor N. The stationary contact of the switch 31 is directly connected to one terminal of the motor 19 by means of a conductor 45 which is electrically connected also to the conductor 43 by a conductor 40. The movable contact of switch 31 is directly connected, as shown, to the line conductor L₁. The thermostatically-operated switch 28 is connected across the conductors 44 and 45 and, when closed, completes a shunt across the contacts of the switch 33. As shown, a thermostatically-operated safety switch 46 may be disposed in the conductor 43 for deenergizing the heater 26 if the temperature of the air heated thereby exceeds a predetermined value. As shown in Fig. 1, the safety thermostat may be disposed in the duct 25 on the downstream side of the heater 26.

As shown in Fig. 2, the knob 41 is provided with indicia which registers with a fixed pointer 47. The indicia appearing on the knob 41 includes two inactive or "off" positions, as shown, and a "Dry" position which is moved opposite the index 47 when a complete or bone-drying operation is to be completed. The indicia on the knob 41 also includes a series indicated as 10, 20, 30, 40, 50 and 60, which represents minutes of operation. It is the latter indicia which is brought in registry with the index 47 when damp drying of the clothes is to be effected. Of course, when adjusted to the 60-minute position a greater amount of moisture will be evaporated from the fabrics in the dryer than when adjusted for shorter periods of operation.

As shown in the drawing, the control is in its inactive or off position and the switches 31, 32 and 33 are maintained open by lobes formed on the cams 34, 35 and 36 and indicated respectively at 34a, 35a and 36a. In adjusting the knob 41 clockwise, as shown in Fig. 2, the lobes of the cams 34, 35 and 36 move from beneath their respective switches 31, 32 and 33 which now close. Accordingly, the main heater 26 is energized through a circuit including the line conductor

L₂, switch 32, heater 26, safety thermostat 46, conductors 43, 40 and 45, switch 31 and the line conductor L₁. The main motor is also energized through the circuit including line conductor L₁, switch 31, conductor 45, motor 19 and conductor N. We are now assuming that the control is adjusted to one of its damp-dry settings, for example, the 40-minute setting. The timer motor will also be energized through a circuit 10 extending from the line conductor L₁, switch 31, conductors 45, 40 and 43, switch 33, timer motor 38 and the line conductor N.

Operator of the dryer will continue for 40 minutes during which time a portion of the moisture in the fabrics being dried is evaporated and a desired amount remains therein in accordance with the operator's wishes. It is understood, at this time, that the thermostatic switch 28 remains open as the temperature within the drying chamber 12 during a damp-drying operation is not elevated to the temperature value at which the thermostat 28 is adjusted to close. At the end of the 40 minutes' operation, in the example given, a cam lobe 35b opens switch 32, whereupon the main heater 26 is deenergized. Operation of the main motor and the timer continues, however, for about 5 minutes in order to cool the fabrics which have been damp dried. At the end of this 5-minute period, cam lobes 34b and 36b open their respective switches 31 and 33 for terminating operation of the motor 19 and the timer motor 38. At this time, the timer 27 is disposed in its second inactive or "off" position.

If a complete or bone-drying operation is to be effected, the timer is adjusted to the "Dry" position wherein all three switches 31, 32 and 33 are closed. Accordingly, heating of the air is effected as well as circulation of the heated air and operation of the timer is carried out for a period of about 15 minutes. At the end of this period of operation, a lobe 36c on the cam 36 opens the switch 33 and terminates operation of the timer 38. Accordingly, the drying operation continues with the timer motor 38 inactive until a predetermined high temperature of, for example, 165° F. effects the closing of the thermostat 28. This is the temperature which prevails when the clothes are completely dried. The closing of the thermostat 28 initiates operation of the timer motor 38 through a shunt circuit which may be traced from the line conductor L₁, the closed switch 31, conductor 45, thermostat 28, conductor 44, timer motor 38 and conductor N. When the lobe 36c rides from beneath the switch 33, the latter closes to complete the parallel timer motor circuit, as described heretofore. At this time, the lobe 35a moves the switch 32 to its "off" position for deenergizing the main heater 26. The main motor 19 continues in operation for circulating cooling air through the dryer until the cam lobes 34a and 36a move their respective switches 31 and 33 to open position, thereby rendering the dryer inactive. The control is now in the "off" position illustrated in Fig. 2. The sequence of operation of the switches 31, 32 and 33 may be clearly followed by reference to the chart in Fig. 3.

From the foregoing, it will be apparent that I have provided an improved control for a clothes dryer including a timing mechanism which may be adjusted for various predetermined periods of operation to obtain different degrees of drying of the fabrics. Operation of the timing mechanism, when adjusted to completely dry the fabrics being treated, is under control of a thermo-

stat responsive to the temperature of the air in the drying chamber so that the timing mechanism functions to terminate a drying operation only when the thermostat reflects a temperature obtaining when the fabrics are completely dried. The control has but a single handle for operation by the operator and the thermostat may be of the nonadjustable type. This control may be readily and economically produced and is reliable in operation.

While I have shown my invention in but one form, it will be obvious to those skilled in the art that it is not so limited, but is susceptible of various changes and modifications without departing from the spirit thereof.

What I claim is:

1. In clothes drying apparatus, the combination of means defining a drying chamber for the material to be dried, means for circulating air through said chamber, means for heating the air, control means for energizing and deenergizing the air heating and air circulating means, a timing motor for operating the control means, said control means including an element for controlling energization of the timing motor, manually operated means for adjusting the control means from an inactive station to an active station for energizing the air heating and air circulating means and means responsive to a predetermined high temperature of the air in the drying chamber for energizing the timing motor for a predetermined period of time, said control means deenergizing the air heating and air circulating means during operation of the timing motor and said element deenergizing the timing motor at the conclusion of said predetermined period of time independently of the temperature-responsive means.

2. In clothes drying apparatus, the combination of means defining a drying chamber for the material to be dried, means for translating air through said chamber, means for heating the air, control means for starting and stopping operation of the air heating means and the air translating means, a timing motor for driving the control means, a control element driven by the timing motor for the control thereof, manually operated means for moving the control means and control element from an inactive position to selective positions thereof for the operation of the timing motor, the air translating means

and the air heating means for selected periods of time at the conclusion of which operation of the air heating means, the air translating means and timing motor is terminated, said control means being movable to an additional active position for the operation of the air heating means and the air translating means, and means effective in said additional active position of the control means for initiating operation of the timing motor in response to a predetermined high temperature of the air in the drying chamber, said timing motor then operating for a predetermined period of time under control of said control element and said control means terminating operation of the air heating means and air translating means during said operation of the timing motor.

3. In clothes drying apparatus, the combination of means defining a drying chamber for material to be dried, motor driven means for circulating air through the drying chamber, electrical means for heating the air, a timing mechanism including switching means for controlling energization of the air heating means and said air circulating means, a timing motor for driving the switching means and a switch controlling the timing motor and driven thereby, means for adjusting said timing mechanism from an inactive position to an active position wherein said switch and switching means are closed, said switch being opened after a predetermined period of time for terminating operation of the timing motor and thermostatically-operated switching means for energizing the timing motor for a second period of operation in response to a predetermined high temperature of the air within said drying chamber, said switching means being actuated to deenergize the air heating and the air circulating means during said second period of operation of the timing motor, and said switch terminating the second period of operation of the timing motor independently of the thermostatically-operated switching means.
